S Thomson,
Clothes Pounder

N° 17240.

Patented May 5, 1857.

UNITED STATES PATENT OFFICE.

SARDIS THOMSON, OF WEST OTIS, MASSACHUSETTS.

CLOTHES-POUNDER.

Specification of Letters Patent No. 17,240, dated May 5, 1857.

To all whom it may concern:

Be it known that I, SARDIS THOMSON, of West Otis, in the county of Berkshire and State of Massachusetts, have invented a new

5 and useful Clothes-Pounder; and I do hereby declare that the following is a full, clear, and exact description of the same, reference being had to the annexed drawings, making a part of this specification, in which—

10 Figure 1 represents a perspective view; Fig. 2, a vertical section in its natural position; Fig. 3, a vertical section with piston forced down to its lowest position; Fig. 4, the different parts of the piston and a nut 15 intended to confine them to the rod; the same letters having reference to like parts in all the figures.

My invention consists in a bell mouthed cylinder nearly closed at the smaller end, 20 a piston, piston-rod, spiral-spring and handle, so combined that a downward force acting upon the handle against the spring at the instant of percussion causes the piston to descend in the cylinder, the same being returned by the recoil of the spring on the removal of the force from the handle, the descent forcing the water through the clothes by the pressure of air, and its return raising the clothes by suction from the bottom of the 25 tub—both of which operations are calculated to agitate the liquid and effect the cleansing of the clothes.

The construction is as follows:

30 A is the cylinder in which the piston B is made to descend by a force applied to the handle E acting through the piston-rod C. The cylinder is bell-shaped at its lower end and sealed at the upper end excepting a perforation to admit the piston-rod C, which 35 rod is inserted in the handle E of which it

is a continuation—that part of it which is between the cylinder and its insertion in the handle being encircled by the spiral spring D.

B is the piston, which, when in a state of 45 rest, is held by the force of the spring at the upper end of the cylinder as seen in Fig. 2, but when the pounder is thrust downward, as soon as the cylinder is arrested by striking against the cloth, the force still acting upon 50 the handle causes the piston to descend to the lower part of the cylinder as seen in Fig. 3, thus expelling the air from the cylinder in the direction of the blow. On the removal of the downward force from the handle the 55 recoil of the spring brings back the piston to its original position at the upper part of the cylinder thereby raising the clothes from the bottom of the tub as mentioned above.

Fig. 4 shows the different parts of the 60 piston *a a* giving a horizontal view of the two metallic plates one of which is placed on either side of the packing of which *b* is a horizontal view these being secured on the piston-rod by the nut *c*.

Having thus described my invention, what 65 I claim as new and desire to secure by Letters Patent, is—

The bell-shaped cylinder in combination with the piston, piston-rod, spring and 70 handle or other equivalents to produce the same effect; viz, the cleansing or washing clothes by agitating the liquid by the pressure of air substantially the same as described above and to be applied to the purposes set forth. 75

SARDIS THOMSON.
